CLAIM

The ornamental design for a phototherapy mask, as shown and described.

DESCRIPTION

FIG. 1 illustrates a top perspective view of a phototherapy mask;

FIG. 2 illustrates a front view of the phototherapy mask thereof;

FIG. 3 illustrates a back view of the phototherapy mask thereof;

FIG. 4 illustrates a left side view of the phototherapy mask thereof;

FIG. 5 illustrates a right side view of the phototherapy mask thereof;

FIG. 6 illustrates a top view of the phototherapy mask thereof;

FIG. 7 illustrates a bottom view of the phototherapy mask thereof; and,

FIG. 8 illustrates a bottom perspective view of the phototherapy mask thereof.

The broken lines in the drawings illustrate portions of the phototherapy mask that form no part of the claimed design.

1 Claim, 8 Drawing Sheets
